Primary Examiner — Sandra Snapp*Assistant Examiner* — Ieisha N Price(74) *Attorney, Agent, or Firm* — Kowert, Hood, Munyon, Rankin & Goetz, P.C.(57) **CLAIM**

The ornamental design for a cylindrical pile with connecting elements, as shown and described.

DESCRIPTION

FIG. 1 is a top and right side perspective view of a cylindrical pile with connecting elements.

FIG. 2 is a top plan view thereof of the embodiment depicted in FIG. 1;

FIG. 3 is a bottom plan view thereof of the embodiment depicted in FIG. 1;

FIG. 4 is a front side elevational view thereof of the embodiment depicted in FIG. 1;

FIG. 5 is a back side elevational view thereof of the embodiment depicted in FIG. 1;

FIG. 6 is a right side elevational view thereof of the embodiment depicted in FIG. 1; and,

FIG. 7 is a left side elevational view thereof of the embodiment depicted in FIG. 1.
